UNITED STATES PATENT OFFICE

143,499

DESIGN FOR A TOILET CABINET OR THE LIKE

Pietro Maniscalco and Peter Maniscalco, Jr.,
Chicago, Ill.

Application March 22, 1945, Serial No. 118,632

Term of patent 14 years

(Cl. D33—18)

To all whom it may concern:

Be it known that we, Pietro Maniscalco and Peter Maniscalco, Jr., citizens of the United States, and residing at Chicago, county of Cook, and State of Illinois, have invented a new, original, and ornamental Design for a Toilet Cabinet or the like, of which the following is a specification, reference being made to the accompanying drawing, forming a part thereof.

Fig. 2 is an end elevational view thereof;
Fig. 3 is a top plan view thereof;
Fig. 4 is a bottom plan view thereof; and
Fig. 5 is a rear perspective view thereof.

We claim:

The ornamental design for a toilet cabinet or the like, as shown.

PIETRO MANISCALCO.
PETER MANISCALCO, JR.
